CLAIM

The ornamental design for a golf putter head, as shown and described.

DESCRIPTION

FIG. 1 is a top perspective view of a golf putter head showing my new design;

FIG. 2 an enlarged left side elevational view thereof;

FIG. 3 is right side elevational view of FIG. 2;

FIG. 4 is a front elevational view of FIG. 2;

FIG. 5 is a rear elevational view of FIG. 2;

FIG. 6 is a bottom plan view; and,

FIG. 7 is a top plan view.

The broken line showing of a handle and shaft is for illustrative purposes only and forms no part of the claimed design.
